(57) CLAIM

The ornamental design for a plastic box for beads storage, as shown and described.

DESCRIPTION

FIG. 1 is a front perspective view of the plastic box for beads storage showing my new design.

FIG. 2 is a front view of the plastic box for beads storage.

FIG. 3 is a rear view of the plastic box for beads storage.

FIG. 4 is a left side view of the plastic box for beads storage.

FIG. 5 is a right side view of the plastic box for beads storage.

FIG. 6 is a top view of the plastic box for beads storage; and,

FIG. 7 is a bottom view of the plastic box for beads storage.

Any shading and cross-hatching are not features of the design but are utilized to illustrate the surface contours of the plastic box for beads storage design in the drawings.

1 Claim, 7 Drawing Sheets
